ANTIBIOTIC COMPOSITIONS

John E. Fahey, Gales Ferry, Conn., assignor to Chas. Pfizer & Co., Inc., New York, N.Y., a corporation of Delaware
No Drawing. Filed July 5, 1963, Ser. No. 293,167
14 Claims. (Cl. 167—65)

This invention relates to novel antibiotic compositions which comprise a tetracycline-type antibiotic together with an organic acid potentiating agent therefor. More particularly, it is concerned with oral compositions of the foregoing type which all contain a succinic acid derivative for the aforesaid purpose, whereby there is thus achieved an enhancement of said antibiotic blood levels in the animal to whom they are so administered.

In this connection, it is to be understood that by the use of the term tetracycline-type antibiotic there is meant to be included not only such amphoteric tetracycline compounds as chlortetracycline, tetracycline, oxytetracycline, 6-demethylchlortetracycline, 6-deoxytetracycline, 6-demethyl-6-deoxytetracycline, 6-demethyl-6-deoxy-7-bromotetracycline, 6-demethyl-6-deoxy-6-methylene-5-oxytetracycline, etc., but also such acid addition salts thereof as the hydrochloride, hydrobromide, hydriodide, sulfate, nitrate, phosphate, acetate, lactate, maleate, citrate, tartrate and ascorbate, as well as base salts of same such as the sodium, potassium, calcium, quaternary ammonium or ethylene diamine salts thereof, or the aluminum gluconate complex or other organic acid complex salts thereof, or any other pharmaceutically acceptable salts of these particular antibiotics which happen to be therapeutically effective per se.

The succinic acid derivative of these novel compositions is an oxa, thia or imino diacid of the aforesaid type and is preferably one selected from the group consisting of 2,2'-oxodisuccinic acid, 2,2'-thioxodisuccinic acid and 2,2'-iminodisuccinic acid, although the corresponding bis anhydrides, as well as the alkali metal and alkaline-earth metal salts thereof, in addition to the corresponding lower alkyl esters of these acids are also useful in this connection. 2,2'-oxodisuccinic acid is described and claimed by R. G. Berg in copending U.S. application Serial No. 255-167, filed January 31, 1963, now U.S. Patent No. 3,128-287, while the other two aforementioned organic acids are both old in the art. These compounds, i.e., the preferred acids, can all be represented by the following generic structural formula:

where X is a member chosen from the group consisting of oxygen, sulfur and imino. Certain other organic acids may also be employed in this connection in lieu of those mentioned above, such as structurally related compounds, including stereoisomers thereof, but the aforementioned disuccinic acids are definitely preferred as previously discussed.

In general, the amount of organic acid potentiating agent to be used with respect to the tetracycline component of the mixture may vary over a wide range, but it is usually more desirable in practice to employ at least

2

a semi-equal amount by weight of the chosen acid and preferably an equal amount or excess of same since it is the cheaper of the two components. Optimum results, however, have been obtained with from about one-half to about thirteen parts by weight of the acid with respect to about one part by weight of the tetracycline component. As previously indicated, all these compositions give remarkably enhanced antibiotic blood levels so that it is now within the realm of reality to achieve much higher tetracycline concentrations in the blood of the animals to whom they are so administered with a given amount of antibiotic compound than heretofore was ever thought possible or conversely, to achieve the same levels with less of the antibiotic than would normally be used alone for this same effect. The advantages afforded the use of this invention are therefore obvious. Moreover, the organic acid potentiating agent can be administered either before or after the administration of the antibiotic provided the time interval between the two is not too excessive, i.e., not more than about 10-20 minutes. However, it is preferred in practice to use the two main components of the mixture together (i.e., at the same time) as will hereinafter be discussed.

A preferred unit dosage form for administering these 25 novel compositions is most conveniently a powdered mixture of the two principal components encased in a soft or hard-shelled gelatin capsule. This dosage form may contain from about 25 mg. up to about 500 mg. of the desired tetracycline together with from about one-half to about thirteen parts by weight of the chosen organic acid. An inert diluent, such as a pharmaceutically-acceptable carrier like starch, lactose or milk sugar, or glucosamine, may also be present if so desired. Conversely, it is also possible to administer these compositions 30 in granulated form as such or else compressed into tablets for oral administration, as well as in the form of aqueous suspensions, elixirs, lozenges, troches, candies and pediatric drops, etc. When administered parenterally, they can be given to the animal in the form of an aqueous dispersion or solution for intravenous injection, or as an organic solution or suspension for intramuscular injection.

Moreover, these compositions may also be administered 35 to domesticated animals, such as cats, dogs, sheep, chickens, turkeys, ducks, hogs, rabbits, and the like, by way of their feeds or drinking water in addition to the direct route previously mentioned. For instance, the oral unit dosage forms previously discussed may be added as such to animal feeds or, and preferably, the novel compositions 40 themselves may be blended into powders for incorporation directly into the feeds. The antibiotic component of the feed may vary anywhere from about 50 g. up to about 1000 g. per ton of feed, while the organic acid potentiating agent must be present to the extent that it 45 is at least about 0.1% by weight based on the total weight of the composition. Needless to say, the tetracycline-type antibiotic component and the organic acid potentiating agent component may either be administered via one component of the animal's feed or else they may be uniformly blended or distributed therein throughout a completely-mixed feed. In this latter connection, it is to be noted that a wide variety of different feed components 50 may be of use in the nutritional diets called for. Thus, the proper feed compositions should normally contain nutritionally-balanced quantities of carbohydrate, fat and

protein, together with the usual vitamin and mineral supplementary sources.

When the novel compositions of this invention are to be used in feeds, a particular type of conventional feed material for just such purposes is one which generally follows the suggested formulae set forth on page six of the authoritative pamphlet issued by the National Research Council of Washington, D.C., on June 1944 and entitled "Recommended Nutrient Allowances for Poultry." For instance, feed compositions are recommended to contain roughly from between about 50% and about 80% of grains, such as ground grain or grain by-products, molasses and other sugar by-products; from between about 3% and about 10% of animal protein, such as fish meal, meatscraps, and the like; from between about 5% and about 30% of vegetable protein, such as soybean oil meal, peanut meal, cottonseed meal, and the like; and from between about 2% and about 5% of minerals, such as bone meal, limestone, and so forth; together with supplementary vitaminaceous sources, such as thiamine, riboflavin, niacin, etc. Furthermore, the compositions of this invention may either be used in said feeds alone or in conjunction with various other antibiotics and chemotherapeutic agents, such as penicillin, bacitracin, sulfaquinoxaline, phenylarsonic acid, hydroxyzine, oleandomycin, and so forth.

In accordance with a more specific embodiment of this invention, a typical feedstuff for poultry may be prepared by mixing the following ingredients together in the proportions by weight specified below:

Ground yellow corn meal	56.65
Soybean oil meal, 50% protein	33.75
Alfalfa meal, 17% protein	2.00
Stabilized animal fat	3.50
Dicalcium phosphate	2.00
Sodium chloride, iodized	0.50
Calcium carbonate	1.00
Trace mineral-vitamin premix ^{1,2}	0.60

¹ The trace mineral mix constitutes 0.05% by weight of the feed and the ingredients contained therein are as follows together with their weight percentages in the premix: manganese, 24%; iodine, 0.48%; iron, 8.0%; copper, 0.8%; zinc, 0.4%; and cobalt, 0.8%.

² The vitamin premix constitutes 0.55% by weight of the feed and the ingredients contained therein are listed below as follows together with their percent concentrations in the premix:

	Percent
Vitamin A (10,000 I.U./g.)	10.0
Vitamin D ₃ (3,000 I.C.U./g.)	10.0
Choline chloride (25%)	35.25
Niacin (80%)	0.55
dl-Calcium pantothenate (45%)	10.0
Riboflavin (4 g./lb.)	0.39
Vitamin B ₁₂ (60 mg./lb.)	0.20
Vigofac ³	30.0
Fine corn meal	3.75

³ Vigofac is the registered trademark name of the Chas. Pfizer & Co., Inc. for unidentified poultry-livestock growth factors obtained from streptomycetes fermentation sources.

Needless to say, many other comparable feeds may also be blended in a similar manner, such as, for example, those which contain lesser amounts of calcium, for instance, up to about 0.5% by weight of calcium as compared to the 1.2% calcium concentration level which is contained in the feeds of the foregoing description.

This invention is further illustrated by the following examples, which are not to be construed in any way as imposing limitations upon the scope thereof. On the contrary, it is to be clearly understood that resort may be had to various other embodiments, modifications and equivalents thereof which readily suggest themselves to those skilled in the art without departing from the spirit of the present invention and/or the scope of the appended claims.

EXAMPLE I

Ten eight-week-old chickens (five male and five female) of the Vantress-White Rock Cross broiler variety were each fed a standard animal feedstuff diet of the

type described previously, which also contained 400 g. of oxytetracycline hydrochloride per ton, together with 2,2'-oxodisuccinic acid at the 0.5% concentration level, based on the total weight of the composition. A similar group was fed the same standard feedstuff diet-antibiotic mixture alone without the oxa acid. At the end of 24 and 72 hours after commencement of the initial antibiotic feeding, all the birds were bled for individual blood samples to determine oxytetracycline sera levels. The results obtained are shown below in the following table:

15	Substance	Average Oxytetracycline Blood Sera Levels (mcg./ml.)		Potentiation Effect (Index)	
		24 hrs.	72 hrs.	24 hrs.	72 hrs.
Oxytetracycline HCl		0.2280	0.2140	100	100
Oxytetracycline HCl plus Oxa acid		0.2286	0.2079	103	125

From the data presented in the above table, it is obvious that 2,2'-oxo-disuccinic acid produced increases in oxytetracycline blood sera levels over that of the controls during assay periods.

EXAMPLE II

Thirty-five (35) eleven-week-old female Vantress-White Rock Cross broilers were divided into five pens of seven birds each. These birds were fed the same standard feed diet as described before and given water continuously throughout the entire test period. One group received a slug dose i.e., an oral dose, of oxytetracycline hydrochloride at the 250 mg. level together with one-half that amount by weight of 2,2'-oxodisuccinic acid, while another group received the same two chemicals in a 1:2 weight ratio, respectively, i.e., 250 mg. oxytetracycline hydrochloride and 500 mg. 2,2'-oxodisuccinic acid. This was then repeated with another group of animals using citric acid in place of the oxa acid at the same two dose levels for comparison purposes (again, a total of 14 animals or seven per group), while a further group served as the controls and were given the antibiotic alone (250 mg. oxytetracycline hydrochloride) without the organic acid. At the end of two and six hours after the initial slug dosing, oxytetracycline blood sera levels were determined by standard assay procedures and the results obtained are presented below in the following table:

55	Organic Acid	Dose (mg.)	Average Oxytetracycline Blood Sera Levels (mcg./ml.)		Potentiation Effect (Index)	
			2 hrs.	6 hrs.	2 hrs.	6 hrs.
Control			0.990	0.794	100	100
Citric acid		125	1.219	0.566	123	71
Do		500	1.788	0.875	181	110
Oxa acid		125	2.816	0.867	234	109
Do		500	6.724	2.266	679	285

65 From the data in the above table, it is obvious that 2,2'-oxodisuccinic acid gives much greater blood levels with oxytetracycline than does citric acid in addition to bring significantly higher than the controls.

EXAMPLE III

The procedure described in Example II is followed except that 2,2'-thio-oxodisuccinic acid is employed in place of the oxa acid used therein on the same weight basis. In like manner, 2,2'-iminodisuccinic acid is also used. In both these cases, the results obtained are sub-

stantially identical with those reported in Example II for the oxa acid.

EXAMPLE IV

The procedure described in Example II is followed except that chlortetracycline is employed in place of oxytetracycline, on the same weight basis, as the antibiotic of choice. In like manner, tetracycline hydrochloride is also employed. In both these cases, comparable results with respect to oxytetracycline are obtained.

EXAMPLE V

The procedure described in Example II was repeated with fifty-four (54) twelve-week-old female Vantress White Rock Cross broilers divided into groups of six birds each. In this case, the oxytetracycline hydrochloride was employed at the 25 mg. slug dose level and the 2,2'-oxodisuccinic acid (oxa acid) was employed at various levels ranging from 80 mg. to 320 mg. in either 5 ml. or 10 ml. amounts (of water). The results obtained in this manner are presented below in the following table, which also includes similar information obtained with citric acid at 320 mg. for comparison purposes:

Potentiator	Dose (mg.)	Treatment Volume (ml.)	Average Oxytetracycline Blood Sera Assay (mcg./ml.)		Potentiation Effect (Index)	
			2 hrs.	6 hrs.	2 hrs.	6 hrs.
Control			5.0	0.322	0.119	100
Oxa acid	80	5.0	0.478	0.259	148	218
Do	80	10.0	0.299	0.148	93	124
Do	160	5.0	0.397	0.220	123	184
Do	160	10.0	0.591	0.170	184	143
Do	320	5.0	0.544	0.219	169	184
Do	320	10.0	0.740	0.263	230	221
Citric acid	320	5.0	0.289	0.156	90	131
Do	320	10.0	0.325	0.143	101	120

From the data in the above table, it is obvious that 2,2'-oxodisuccinic acid (oxa acid) is an effective potentiating agent for oxytetracycline when administered in slug doses and that approximately one-fourth the quantity of this compound with respect to the amount of citric acid employed produced essentially the same results at the end of the 6-hour period.

EXAMPLE VI

The procedure described in Example V is followed except that 500 mg. of oxytetracycline hydrochloride is employed instead of 25 mg. In like manner, tetracycline hydrochloride and chlortetracycline hydrochloride are each similarly employed at both these same dose levels, i.e., at 25 mg. and 500 mg. respectively. In all these cases, the results obtained are substantially the same with respect to degree of potentiation as those previously reported in Example V. Comparable results are also obtained in all these cases when 2,2'-thiooxodisuccinic acid and 2,2'-iminodisuccinic acid are each individually employed in place of the oxa acid previously used.

EXAMPLE VII

Seventy (70) six-week-old chickens of the Vantress-White Rock Cross broiler variety were divided into seven groups of five male and five female chicks each and subjected to the general procedure of Example I except that different amounts of 2,2'-oxodisuccinic acid were employed or that 2,2'-thiooxodisuccinic (thia acid) or 2,2'-iminodisuccinic acid (imino acid) were each individually

employed in lieu thereof. The results obtained in this manner are summarized below in the following table:

5	Potentiating Compound	Concn. Level, percent	Average Oxytetracycline Blood Sera Levels (mcg./ml.)		Potentiating Effect (Index)	
			24 hrs.	72 hrs.	24 hrs.	72 hrs.
10	None		0.209	0.221	100	100
	Oxa acid	0.01	0.188	0.245	90.1	111
	Do	0.1	0.223	0.240	106.6	108.8
	Do	1.0	0.242	—	115.9	—
	Do	2.0	0.360	—	179.9	—
	Thia acid	0.1	0.219	0.220	104.7	99.7
	Do	1.0	0.290	0.288	138.4	121.2

15 From the above table, it is obvious that 2,2'-oxodisuccinic acid (oxa acid) achieved its greatest potentiating effect at the 2.0% concentration level and that 2,2'-thiooxodisuccinic acid (thia acid) is quite similar to the aforementioned oxa acid with respect to its potentiating effect at the two different dose levels at which it was tested.

20 In like manner, 2,2'-iminodisuccinic acid proved to be equally effective as a potentiating agent as the thia acid when tested at the same two dose levels as indicated above.

EXAMPLE VIII

25 A total of sixteen fasting (for about 15 hrs.) dogs, each weighing anywhere from about 15 to 49 lbs., were used in this experiment. Seven of the dogs received the standard human capsule of 250 mg. of oxytetracycline hydrochloride with glucosamine, while the remaining nine each received the experimental capsule that contained 250 mg. of oxytetracycline hydrochloride together with 250 mg. of 30 2,2'-oxodisuccinic acid. At the end of three and six hours after the capsule administration, blood samples for serum assay were obtained from the dogs. The results obtained in this manner are presented below in the following table:

40	Substance	Average Oxytetracycline Blood Sera Levels (mcg./ml.)		Potentiation Effect (Index)	
		3 hrs.	6 hrs.	3 hrs.	6 hrs.
45	Oxytetracycline HCl plus Glucosamine	0.488	0.304	100	100
	Oxytetracycline HCl plus Oxa acid	0.833	0.518	181	170

EXAMPLE IX

50 Sixty-four (64) eight-week-old chickens of the Vantress-White Rock Cross broiler variety were divided into groups of four male and four female birds each. They were then each fed the standard basal animal feedstuff ration without added antibiotic and subjected to the following treatment, employing oxytetracycline hydrochloride (250 mg.) and organic acid potentiating agent at the two dose levels indicated, and including both water solution and capsule form for the 2,2'-oxodisuccinic acid (oxa acid).

65	Potentiating Agent	Potentiating Dose (mg./ml.)	Dosage Form	Average Oxytetracycline Blood Sera Levels (mcg./ml.)	
				3 hrs.	6 hrs.
70	None		Water	1.817(100)	1.423(100)
	Do		Capsule	1.717(100)	0.491(100)
	Oxa acid	250	Water	6.333(349)	4.258(299)
	Do	250	Capsule	5.282(306)	2.025(412)
	Do	500	Water	10.233(563)	4.717(381)
	Do	500	Capsule	12.900(751)	4.150(845)
	Thia acid	250	do	2.592(151)	1.656(337)
	Imino acid	250	do	6.238(363)	1.950(397)

From the data presented in the above table (where the potentiation indices are given in parentheses), it can be calculated that average potentiating effects of 329 and 787 were obtained with 250 mg. and 500 mg. capsule doses of 2,2'-oxodisuccinic acid (oxa acid), respectively, as compared to corresponding values of 231 and 453 for the aqueous solutions containing same. The analogs of 2,2'-oxodisuccinic acid, viz., 2,2'-thioxodisuccinic acid (thia acid) and 2,2'-iminodisuccinic acid (imino acid), also produced marked potentiating effects.

EXAMPLE X

Sixty (60) eight-week-old chickens of the Vantress-White Rock Cross broiler variety were divided into six groups of five male and five female birds each and fed the standard ration used before. One set of three such groups received oxytetracycline hydrochloride at levels of 200, 500, and 1000 grams per ton, respectively, together with 2,2'-oxodisuccinic acid (oxa acid) at the 2.0% concentration level. The other set of birds received the antibiotic alone, without the added acid, at the same three dose levels previously indicated. At the end of 24, 48 and 72 hours after initiation of the feeding, the birds were bled by heart puncture in order to run blood sera assays on the resulting samples. The results obtained in this manner are summarized below in the following table:

two compounds at the end of the aforementioned time periods:

Antibiotic	Oxa Acid Concn. Level, percent	Average Antibiotic Potentiation Indices	
		24 hrs.	72 hrs.
Oxytetracycline.....	None	100	100
Do.....	2	241	198.5
Chlortetracycline.....	None	100	100
Do.....	2	164.5	190.5

From the data presented in the above table, it is obvious that 2,2'-oxodisuccinic acid produced a potentiation of the oxytetracycline and chlortetracycline blood levels.

EXAMPLE XIII

A group of five albino rats received an initial dose of 6-demethyl-6-deoxy-6-methylene-5-oxytetracycline hydrochloride (GS-2876) orally via an oral tube at the 125 mg./kg. level. A second group received the same dose together with an equal amount of 2,2'-oxodisuccinic acid (125 mg./kg.). A third group received no antibiotic nor oxa acid whatsoever and served as the controls, while a fourth group received the oxa acid alone. The animals were then placed in metabolism cages for 18 hours post

Oxytetracycline Concn. Levels (g./T)	Potentiating Agents	Average Oxytetracycline Blood Sera Levels (mcg./ml.)			Potentiation Effect (Index)		
		24 hrs.	48 hrs.	72 hrs.	24 hrs.	48 hrs.	72 hrs.
200-----	None-----	0.117	0.127	0.099	100	100	100
500-----	do-----	0.808	0.342	0.252	100	100	100
1,000-----	do-----	0.586	0.697	0.677	100	100	100
200-----	Oxa Acid-----	0.198	0.273	0.214	169	215	216
500-----	do-----	0.560	0.502	0.590	181	147	234
1,000-----	do-----	1.014	1.199	1.380	173	172	209

From the above table, it is obvious that 2,2'-oxodisuccinic acid (oxa acid) at the 2% concentration level potentiates oxytetracycline at all three dose levels tested.

EXAMPLE XI

The procedure described in Example X is repeated except that oxytetracycline hydrochloride is now employed at concentration levels of 50, 100 and 150 grams per ton, respectively. In each and every case, the results obtained are comparable in order of magnitude to those previously reported in the foregoing example for the higher concentration values.

EXAMPLE XIII

Forty-eight (48) young chickens of the Vantress-White Rock Cross broiler variety were placed into pens of six male and six female birds each. The animals were then fed the standard animal basal feedstuff ration, with one group (12 animals) receiving oxytetracycline at the 400 g. per ton level together with 2,2'-oxodisuccinic acid in the amount indicated below, while another group served as the controls and received no such oxa acid. In like manner, these tests were again repeated with two other groups of animals only employing chlortetracycline in place of the oxytetracycline. At the end of 24 and 72 hours after initiation of said treatment, the birds were bled in order to determine blood sera levels on their samples. The results obtained in this manner are summarized below in the following table, which indicates the average antibiotic potentiation indices for each of these 75

dose and the total volume of urine excreted was collected. Food was withheld from the animals throughout this entire test period, but water was given them *ad libitum*. The results obtained in this manner are shown below in the following table:

Substance	Oral Dose (mg./kg.)	Average Percent Dose Excreted (percent)
None		No activity
Oxa Acid	125	No activity
GS-2876	125	2.28
GS-2876 plus Oxa acid	125	13.66

From the data presented in the above table, it can be seen that 2,2'-oxodisuccinic acid (oxa acid) at the 125 mg./kg. level gives much greater urinary excretion levels (about six times as much) with 6-demethyl-6-deoxy-6-methylene-6-oxytetracycline hydrochloride than does the antibiotic itself when used alone.

What is claimed is:

- What is claimed is:

  1. An antibiotic composition comprising a tetracycline-type antibiotic and a compound selected from the group consisting of 2,2'-oxodisuccinic acid, 2,2'-thioxodisuccinic acid and 2,2'-iminodisuccinic acid.
  2. A composition as claimed in claim 1 wherein the tetracycline-type antibiotic is oxytetracycline.
  3. A composition as claimed in claim 1 wherein the tetracycline-type antibiotic is tetracycline.

4. A composition as claimed in claim 1 wherein the tetracycline-type antibiotic is chlortetracycline.

5. An antibiotic composition as claimed in claim 1 wherein the amount of organic acid present by weight is at least equal to one-half that of the tetracycline antibiotic.

6. An antibiotic composition in unit dosage form suitable for oral administration comprising from about 25 mg. up to about 500 mg. of a tetracycline-type antibiotic and from about one-half to about thirteen parts by weight of a compound selected from the group consisting of 2,2'-oxodisuccinic acid, 2,2'-thiooxodisuccinic acid and 2,2'-iminodisuccinic acid with respect to the tetracycline antibiotic.

7. A composition as claimed in claim 6 wherein the organic acid is 2,2'-oxodisuccinic acid.

8. A composition as claimed in claim 6 wherein the organic acid is 2,2'-thiooxodisuccinic acid.

9. A composition as claimed in claim 6 wherein the organic acid is 2,2'-iminodisuccinic acid.

10. An animal feed composition comprising a nutritionally-balanced animal feed to which there is added a tetracycline-type antibiotic and a compound selected from the group consisting of 2,2'-oxodisuccinic acid, 2,2'-thiooxodisuccinic acid and 2,2'-iminodisuccinic acid.

11. A feed composition as claimed in claim 10 wherein the antibiotic is present at a concentration level that is in the range of from about 50 g. up to about 1000 g. per ton of feed.

12. A feed composition as claimed in claim 10 wherein the organic acid member is present to the extent of at least about 0.1% by weight based on the total weight of the composition.

13. A method of potentiating the blood levels of a tetracycline-type antibiotic when orally administered, which comprises the step of orally administering the tetracycline-type antibiotic in conjunction with a compound selected from the group consisting of 2,2'-oxodisuccinic acid, 2,2'-thiooxodisuccinic acid and 2,2'-iminodisuccinic acid.

14. A method as claimed in claim 13 wherein the amount of organic acid employed by weight is at least equal to one-half that of the tetracycline-type antibiotic.
